UNITED STATES PATENT OFFICE.

HARRY O. RUGH, OF CHICAGO, ILLINOIS, ASSIGNOR TO WESTERN TELEGRAPHONE COMPANY, OF MINNEAPOLIS, MINNESOTA, A CORPORATION OF SOUTH DAKOTA.

SIGNALING APPARATUS.

No. 831,526.

Specification of Letters Patent.

Patented Sept. 18, 1906.

Application filed January 8, 1904. Serial No. 188,210.

To all whom it may concern:

Be it known that I, HARRY O. RUGH, a citizen of the United States, residing at Chicago, in the county of Cook and State of Illinois, have invented a certain new and useful Improvement in Signaling Apparatus, of which the following is a full, clear, concise, and exact description, reference being had to the accompanying drawing, forming a part 10 of this specification.

My invention relates to signaling apparatus and systems.

In accordance with one feature of my invention I employ a relay having a polarized armature in combination with a suitable source of signaling-current for polarizing the relay alternately, thereby effecting the operation of the armature and a signal-producing device governed by the armature. The 15 relay preferably presents two poles to the armature, the winding of the relay being such that these poles are of unlike sign, so that when alternating current is impressed upon the relay each pole alternates in sign, the 20 armature being at such times continuously vibrating out of operative contact with the unlike poles or contacts desirably associated therewith when a source of high-frequency calling-current is employed. I preferably so 25 arrange the apparatus that when such calling-current is not impressed upon the relay a signal controlled by the armature will remain quiet, while when such calling-current is impressed upon the relay the armature will 30 effect the production of signals owing to its rapid vibration.

In the preferred embodiment of my invention I employ a subsidiary or secondary signaling-circuit desirably having one terminal 40 in the aforesaid armature and the other terminal in the frame of the said relay, the armature being adapted for electrical connection with one or the other of the said poles that desirably serves to normally complete 45 the said subsidiary circuit. There is desirably included in the said subsidiary circuit a signal-producing electromagnet, such as the magnet of an ordinary make-and-break direct-current vibrating bell. This subsidiary 50 circuit desirably includes a closed-circuit battery, the signal-producing magnet being thus normally energized when the apparatus is idle. When the apparatus is

started in operation during the presence of high-frequency calling-current upon the 55 main signaling-circuit, the subsidiary circuit is broken at the armature of the relay, the armature then being out of operative electrical contact with both of the poles, an ordinary make-and-break circuit being then 60 established about the signal-producing electromagnet which is caused to effect a signal, such as the sound of the bell.

In the preferred embodiment of my invention the relay-armature is desirably of soft 65 iron and is itself not materially magnetized permanently. The permanent magnet is disposed near this armature, whereby magnetism is induced in the armature. The strength to which the armature is magnetized or polarized by induction may be regulated by making the permanent magnet adjustable, the magnet being desirably pivoted or otherwise movably mounted for the purpose of this adjustment. By this means all 70 mechanical adjustment of the relay-armature may be avoided. This form of relay I believe to be novel with me, and in it I prefer to employ two poles between which the armature is disposed; but I do not wish to 75 be limited in all embodiments of the invention to a relay wherein this disposition of the armature is effected.

The device of my invention is adapted for a wide variety of uses and is particularly 80 serviceable in connection with composite telephony and telegraphy, though it is not to be restricted to this use.

I will explain my invention more fully by reference to the accompanying drawing, 85 which illustrates one type of apparatus designed in accordance with the invention.

I have indicated a main signaling-conductor *a*, that may have included therewith a suitable source of calling-current *b*, located 90 at the station from which signals are being sent, which signaling-current is desirably a high-frequency alternating current, particularly where the invention is adapted for use in systems of composite telephony and telegraphy, there being indicated a circuit-closer *c* for the purpose of associating the source of calling-current with the said circuit. The 95 said circuit includes the winding of a relay *d*, located at the signal-receiving station, this 100 winding being desirably divided into two 105

coils *e* and *f*, that are placed about the cores *g* and *h*, which are desirably of soft iron and preferably united at their heel portions by a soft-iron yoke *i*, the magnetic circuit being complete save for a slight space between the inner ends of the cores *g* and *h*, which cores are preferably placed in axial alinement. The coils are so relatively disposed or wound that when current is passed through the same in a given direction the adjacent poles of the cores *g* and *h* are of unlike sign. The swinging armature *k*, anchored at one end and substantially free at the other, is polarized and is normally desirably electrically connected with one or the other of the poles of the cores *g* and *h*, the poles being desirably provided with platinum contacts, as is the armature, it being assumed that the armature is interposed between the pair of poles. The armature is thus desirably caused to normally maintain the subsidiary or secondary signaling-circuit *l* closed. The terminals of this secondary circuit reside in the armature and desirably in a contact carried by the core or cores of the relay. When signaling-current is passed over the main signaling-circuit, the armature is moved out of operative contact with the frame of the relay, whereupon the secondary signaling-circuit *l* is opened. This secondary circuit includes a signal presenting or effecting electromagnet *m*, which in this instance controls a signal in the form of a gong *n*, the armature of the magnet carrying a clapper *o* for striking the gong. The same armature also carries a contact-spring *p*, that has a back contact *q*, the contacts *p* and *q*, with their connections *r* and *s*, establishing a tertiary signaling-circuit that is brought into action when the secondary circuit is open at the armature *k*, the battery *t* being desirably common to both the secondary and tertiary circuits. As long as the armature *k* is in open circuit, which is during the presence of suitable signaling-current upon the line, the signaling-magnet *m* will remain in operation after the manner of an ordinary vibrating bell.

When the apparatus is to be employed in connection with composite telephone and telegraph lines, the signaling-current that is most desirably employed is one of high frequency. I have indicated a line *t'*, that may serve to carry both telephonic and telegraphic currents; but I have not deemed an illustration of the apparatus to be used upon such a line for these purposes to be essential to an understanding of my present invention.

The permanent magnet *v* serves to polarize the armature of the relay. This magnet permanently polarizes the armature and is made adjustable, so that the strength of the coaction between the relay-poles and armature may be regulated.

It will be seen that I have provided a relay

wherein the armature is subject to the adjusting influence of a magnet without the necessity of modifying the physical relations of the relay-poles and the armature.

It is obvious that changes may be made in the apparatus I have herein disclosed without departing from the spirit of my invention. I do not, therefore, wish to be limited to the precise mechanism and circuits illustrated; but,

Having thus described my invention, I claim as new and desire to secure by Letters Patent—

1. The combination with a relay having two opposed polar portions and provided with coils wound to secure in said polar portions polarities of unlike sign and having a permanently-polarized armature interposed between the same, of a source of high-frequency current in circuit with said coils to simultaneously cause in said polar portions polarities of unlike sign, signal-producing means controlled by the armature and a subsidiary signaling-circuit placed in one operative condition by the armature when it is idle and attracted toward one or the other of the said poles and placed in an alternatively-operative condition when the armature is alternately attracted by said poles, substantially as described.

2. The combination with a relay having two opposed soft-iron polar portions and provided with coils wound to secure in said polar portions polarities of unlike sign and having a permanently-polarized armature interposed between the same, of a source of high-frequency current in circuit with said coils to simultaneously cause in said polar portions polarities of unlike sign, signal-producing means controlled by the armature and a subsidiary signaling-circuit placed in one operative condition by the armature when it is idle and attracted toward one or the other of the said poles and placed in an alternatively-operative condition when the armature is alternately attracted by the poles, substantially as described.

3. The combination with a relay having two opposed polar portions and provided with coils wound to secure in said polar portions polarities of unlike sign and having a permanently-polarized armature interposed between the same, of a source of high-frequency current in circuit with said coils to simultaneously cause in said polar portions polarities of unlike sign, signal-producing means controlled by the armature, a subsidiary signaling-circuit placed in one operative condition by the armature when it is idle and attracted toward one or the other of the said poles and placed in an alternatively-operative condition when the armature is alternately attracted by the poles, and an adjusting-magnet for polarizing the armature, substantially as described.

4. The combination with a relay having two opposed soft-iron polar portions and provided with coils wound to secure in said polar portions polarities of unlike sign and having a permanently-polarized armature interposed between the same, of a source of high-frequency current in circuit with said coils to simultaneously cause in said polar portions polarities of unlike sign, signal-producing means controlled by the armature, a subsidiary signaling-circuit placed in one operative condition by the armature when it is idle and attracted toward one or the other of the said poles and placed in an alternatively-operative condition when the armature is alternately attracted by the poles, and an adjusting-magnet for polarizing the armature, substantially as described. 5. The combination with a relay having two opposed polar portions and provided with coils wound to secure in said polar portions polarities of unlike sign and having a permanently-polarized armature interposed between the same, of a source of high-frequency current in circuit with said coils to simultaneously cause in said polar portions polarities of unlike sign, signal-producing means controlled by the armature, a subsidiary signaling-circuit placed in one operative condition by the armature when it is idle and attracted toward one or the other of the said poles and placed in an alternatively-operative condition when the armature is alternately attracted by the poles, and an adjusting-magnet for polarizing the armature, substantially as described. 6. The combination with a relay having two opposed soft-iron polar portions and provided with coils wound to secure in said polar portions polarities of unlike sign and having a permanently-polarized armature interposed between the same, of a source of high-frequency current in circuit with said coils to simultaneously cause in said polar portions polarities of unlike sign, signal-producing means controlled by the armature, a subsidiary signaling-circuit placed in one operative condition by the armature when it is idle and attracted toward one or the other of the said poles and placed in an alternatively-operative condition when the armature is alternately attracted by the poles, and an adjusting-magnet for polarizing the armature, substantially as described. 7. The combination with a relay having two opposed soft-iron polar portions and provided with coils wound to secure in said polar portions polarities of unlike sign and having a permanently-polarized armature interposed between the same, of a source of high-frequency current adapted for inclusion in circuit with said coils to simultaneously cause in said polar portions polarities of unlike sign, signal-producing means controlled by the armature and a normally closed subsidiary signaling-circuit placed in one operative condition by the armature when it is idle and attracted toward one or the other of the said poles and placed in an alternatively-operative condition when the armature is alternately attracted by the poles, said armature controlling one terminal of the signaling-circuit, the other terminal of the circuit being duplicated, one or the other of the duplicated terminals being normally connected with the terminal controlled by the armature. 8. The combination with a relay having two opposed soft-iron polar portions and provided with coils wound to secure in said polar portions polarities of unlike sign and having a polarized armature interposed between the same, of a source of high-frequency current adapted for inclusion in circuit with said coils to simultaneously cause in said polar portions polarities of unlike sign, signal-producing means controlled by the armature and a normally closed subsidiary signaling-circuit placed in one operative condition by the armature when it is idle and attracted toward one or the other of the said poles and placed in an alternatively-operative condition when the armature is alternately attracted by the poles, said armature controlling one terminal of the signaling-circuit, the other terminal of the circuit being duplicated, one or the other of the duplicated terminals being normally connected with the terminal controlled by the armature. In witness whereof I hereunto subscribe my name this 14th day of March, A. D. 1903. HARRY O. RUGH.
